UNITED STATES PATENT OFFICE.

LAWRIE L. WITTER, OF HARTFORD, CONNECTICUT.

SAFETY RAZOR AND STROPPER.

Application filed December 12, 1922. Serial No. 606,380.

To all whom it may concern:

Be it known that I, LAWRIE L. WITTER, a citizen of the United States, residing at Hartford, in the county of Hartford and State of Connecticut, have invented certain new and useful Improvements in Safety Razors and Stroppers, of which the following is a specification.

This invention relates to safety razors and stropping means for the blades thereof. The primary object of the invention is to provide an improved safety razor and stropping means in combination with a blade holder, the holder with a blade therein being adapted to either be rigidly supported in shaving position in the razor or to be pivotally supported in stropping position in the stropper.

In the drawing, I have illustrated two forms of my invention. In one form, the blade holder is mounted on the razor both for shaving and stropping. For shaving, the holder and blade are rigidly secured in the razor with the blade in shaving position, and for stropping, the razor with the holder and blade pivotally mounted therein is inserted in the stropper as a unit. In the other form of my invention, the holder and blade are rigidly secured in the razor for shaving and are removed from the razor as a unit and pivotally supported in the stropper for stropping. In its preferred form, the blade holder is so constructed that the blade may be easily changed when desired and the construction of the razor is such that the holder in no way interferes with the mounting of the blade therein for shaving. Furthermore, the stropper is so constructed, relative to the razor and blade holder, that such elements are adapted to be received therein in a manner to readily cooperate with the stropping means.

Another object of the invention is to provide means adapting a razor of the double cutting edge type and particularly such a razor of the Gillette type, as illustrated, to a stropper whereby the razor blade may be quickly and conveniently stropped before shaving, the said means including a blade holder adapted with a blade therein to be readily mounted in shaving position in the razor and to be pivotally mounted in the stropper wherein both cutting edges of the blade may be quickly stropped.

With the above and other objects in view, my invention consists in the features of construction and operation set forth in the fol-

lowing specification and illustrated in the accompanying drawing. In such drawing annexed hereto and forming a part of this specification, I have shown certain specific embodiments of my invention but it will be understood that the invention can be otherwise embodied and that the drawing is not to be construed as defining or limiting the scope of the invention, the claims appended to this specification being relied upon for that purpose.

Referring to the figures of the drawing: Figure 1 is a perspective view of a razor embodying one form of my invention.

Fig. 2 is a longitudinal section thereof.

Figs. 26 and 27 show modifications hereinafter described.

Fig. 28 is a top plan view of the pinion shown in Fig. 27.

Fig. 29 is a perspective view illustrating a modified form of blade holder supporting a blade.

Figs. 30 and 31 are diagrammatic views illustrating the stropping action of the stropper.

Referring first to the form of my invention shown in Figs. 1 to 16 of the drawing, 1 indicates the head or inner guard of a safety razor of well known construction, a handle 2 being integrally or otherwise secured to the head 1. The head or guard 1 is provided with guard teeth 3 along the opposite edges thereof and the outer blade engaging surface 4 of the head is preferably transversely curved as illustrated. 5 indicates the usual outer guard, the inner blade engaging face of which is transversely curved to cooperate with the curved surface 4 of the head 1. The guard 5 is provided with a pair of cylindrical lugs 6 adapted to extend through the blade and head 1 for holding such elements in the proper relative positions in the razor. A threaded shank 7 on the guard 5 extends into the handle 2 and is engaged by a threaded sleeve 8 therein whereby the outer guard 5 may be drawn 40 toward the head in a manner to clamp the blade in shaving position between such elements. The sleeve is provided with a knurled head 9 whereby the same may be rotated.

50 My invention, as shown in Figs. 1 to 16 of the drawing, contemplates the mounting of the blade 10 on the razor either rigidly for shaving or pivotally for stropping. To such end I provide a blade holder comprising two relatively thin flexible plates 11 and 12. Both such plates are perforated at 13, 14 and 15 to receive the lugs 6 and shank 7, the plate 12 being struck out to provide circular flanges about the perforations 13 and 14 which flanges are received within the corresponding perforations on the blade and plate 11 as shown in Fig. 9. The plate 11 is plane rectangular in form and the ends of plate 12 are bent over at 16 in a manner to receive the blade 10 and plate 11 therein,

the ends 16 being flexible and bent to a shape permitting the plate 11 to snap thereby into a position to hold such plate firmly in contact with the blade.

Each end of the plate 12 of the blade holder has pivotally mounted thereon a supporting element 17, one element 17 being mounted on a pivot pin 18 extending from one end of the plate 12 and the other element 17 being mounted on a pivot pin 19 extending from the other end of the plate 12. A small pinion 20, to be hereinafter mentioned, is also secured to the pin 19. Formed on the ends of the head 1 are rearwardly extending lugs 21 having rearwardly extending guideways therein for slidably receiving the elements 17. A spring clip 22 on each lug 21 is provided with a pin 23 therein normally engaging in a groove 24 in its element 17 whereby to limit the outward movement of the elements in the guideways. The free end of each clip is slightly curved upwardly at 22a whereby the same may be lifted to permit the elements to be removed from the head. Such operation becomes necessary only when it is desired to change the blade in the holder.

Both guards 1 and 5 are preferably grooved longitudinally at 25 and 26 respectively for receiving therein the plates 11 and 12 of the blade holder. In Figs. 1, 2, 10, 11 and 12, the several parts of the razor are shown in the shaving position. It should be understood that the parts 11 and 12 of the blade holder are flexible whereby the same readily flex to the curved contour of the blade engaging surfaces of the guards. Also the recesses 25 and 26 are so shaped as to fully receive the plates 11 and 12 therein whereby the blade is engaged by the adjacent curved surfaces of the guards in substantially the same manner as though the blade alone was held therebetween. Thus in its shaving position, the blade 10 is held secured between the adjacent curved surfaces of the guards with each cutting edge thereof extending along the guard teeth 3 directly over a guard groove 27 formed in such teeth.

In Figs. 13 to 16, inclusive, I have illustrated a stropper having the razor just described mounted therein in blade stropping position. This stropper comprises a box-like frame 28 having an eye 29 thereon for engaging over an anchoring hook 30. One side wall is cut away at 31 and a portion 32 of the top wall adjacent thereto is pivoted at 33. This pivoted portion 32 is broken away in Fig. 13 to illustrate the razor and operating mechanism beneath the same. Between and rotatably mounted at its ends in the side walls of the frame is a roller 34. Rigidly secured to one end of this roller is an arm 35 provided on its free end with gear teeth 36 adapted to mesh with the pinion 20 on the blade holder. The side wall adjacent the

gear teeth 36 is perforated at 37 to receive the pivot pin 19 projecting beyond the end of the pinion 20. This perforation is so positioned that the pinion 20 must accurately mesh with the gear teeth 36 when the pin 19 is engaged therein.

The bottom wall and one side wall of the box 28 is cut away at 38 to receive the handle 2 of the razor therein. A pair of spring clips 39 and 40 having their ends secured to the side walls of the box are restricted at their central portions in a manner to receive and grip the handle therebetween. It will be noted that the handle 2 adjacent the head 1 is formed of a diameter smaller than the remaining portion of the handle. The clips, as shown in Fig. 14, are shaped to accurately fit this smaller portion in a manner to hold the razor properly positioned in the stropper.

Rotatably mounted in the free end of the stropper is a pair of strop guiding rollers 41 and 42, the roller 41 being mounted in the body of the box 28 and the roller 42 being mounted in the free end of the pivoted portion 32. Secured to the frame 28 at each end of the roller 41 is a spring clip 43 extending toward the roller 42. The free end of each such clip is slightly curved outwardly and formed with a perforation therein for receiving the end of a pin 44 rotatably supporting the ends of the roller 42. The construction is such that the pivoted portion 32 may be automatically snapped into the operative position shown in Figs. 14 and 15 wherein the rollers 41 and 42 are securely held in the spaced position illustrated. A flexible strop 45 is adapted to extend between the rollers 41 and 42 and around the blade and its holder and the roller 34, as illustrated. Means, as a curved plate 46, may also be provided if desired for assisting the operator in passing the strop around the roller 34.

In Figs. 1, 2, 10, 11 and 12, the razor is shown in its shaving position, the blade with its holder in the recesses 25 and 26 being held between the inner guard 1 and the outer guard 5 in substantially the same manner as though the blade alone was held therebetween. When it is desired to strop the blade, the sleeve 8 is rotated to release the outer guard 5 which is entirely removed from the razor. The razor is then placed in the stropper between the holding clips 39 and 40 as illustrated in Figs. 13 to 16. In such position the end of pin 19 engages in the perforation 37 whereby the pinion 20 is in mesh with the gear teeth 36.

The strop 45 may be threaded through the razor and placed in stropping position either before or after the razor is entirely seated in the stropping position just described, whichever is the more convenient for the operator. It should be understood

that during such placing of the strop, the pivoted portion 32 of the box may be left wide open. This pivoted portion is thereafter snapped into the position shown in full lines (Fig. 14) whereupon the parts are ready for the stropping operation.

The stropping action is shown diagrammatically in Figs. 30 and 31. As the strop is pulled in one direction, the arm 35 operates on the pinion 20 to rotate the holder 75 and blade in a direction to hold the opposite edges of the blade against the receding strop, and as the direction of the strop is reversed, the holder and blade are rotated in the opposite direction in the same manner. Both edges of the blade are thus stropped simultaneously and automatically. It should furthermore be noted (Fig. 14) that the rollers 41 and 42 are so positioned relative to the diameter of the roller 34 and 80 to the position of the perforation 37 that the two portions of the strop are held parallel with the blade accurately positioned centrally therebetween.

Another form of my invention is illustrated in Figs. 17 to 28 inclusive. The razor in this form is substantially the same as that just described except that no means is provided for pivoting the blade holder thereon. Briefly, this razor comprises inner 90 and outer guards 1' and 5' and a handle 2' rigidly secured to the inner guard 1', the inner guard or head being furthermore provided with guard teeth 3'. A knurled head 9' provides for drawing the outer guard toward the inner guard as illustrated in Fig. 2.

In this form of the invention I provide a blade holder as an element entirely separate from the razor. Otherwise the holder is substantially the same as that shown in Figs. 8 and 9. As shown in Fig. 21, this holder comprises two plates 11' and 12' formed the same as plates 11 and 12 shown in Fig. 9 and heretofore described. A blade 110 10' is illustrated as held between the plates 11' and 12'. On one end of the plate 12' is a pivot pin 18' and on the other end is a pinion 20' having a pin 19' centrally thereof. The adjacent curved surfaces of the 115 guards 1' and 5' are recessed at 25' and 26' to receive the plates 11' and 12' therein and, as illustrated in Figs. 17, 18 and 19, the holder and its blade may be clamped in shaving position between such guards in substantially the same manner as though the blade alone were clamped therein.

In Figs. 22 to 25 inclusive, I have illustrated a stropper particularly adapted to receive the holder and blade shown in Figs. 125 20 and 21. This stropper is of a box-like construction similar to but smaller than that shown in Figs. 13 to 16. Certain parts of the stropper which are substantially the same as corresponding parts shown in Figs. 130

13 to 16 and above described are labeled with corresponding primed numerals in Figs. 22 to 25 and will therefore not be described in detail. Each side wall 48 of the box is perforated at 37' to receive the pivot pin 19' therein. The opposite side wall 49 is provided with a lateral projection 50. This projection is struck out to form an inclined groove 51 therein leading into a perforation 52 for receiving the pin 18' of the blade holder.

When it is desired to strop the blade shown in Figs. 17 to 24, the outer guard 5' is removed as is also the blade holder and blade (Fig. 20). The hinged portion 32' being wide open and one end of the strop held outward adjacent thereto (Fig. 23), the pin 19' of the blade holder is inserted in the perforation 37' and the pin 18' slid inwardly along the groove 51 until such pin snaps into the perforation 52. As shown in Fig. 23, this perforation is directly in axial alignment with the perforation 37' whereby the blade is held accurately pivoted on an axis midway between the parallel portions of the strop. The pivoted portion 32' is next snapped shut and the razor stropped in the manner heretofore described. The blade and holder may thereafter be removed by opening the pivoted portion 32' and lifting the projection 50.

It should be clearly understood that the details of the invention are not limited to those herein shown and described. For instance, the ends of the blade holder may be supported in various ways. In Figs. 26, 27 and 28, I have illustrated other methods of supporting such ends. In Fig. 26, the side wall 48 instead of being perforated at 37' is provided with a pin 53 therein adapted to engage within a central hole in a pinion 54 secured to the end of the blade holder plate 12'. Such construction eliminates the projecting pin 19' on the blade holder above described. In Figs. 27 and 28, I have illustrated a further modification wherein a pinion 55 is rotatably mounted on a bushing 56 supported in the wall 48. The bushing and pinion are provided with holes 57 and 58 therein for respectively receiving pins 59 and 60 projecting from the end of the blade holder plate 12'. Such construction eliminates the placing of the pinion on the blade holder. Further modifications of the construction illustrated may likewise be made without departing from the spirit of the invention.

In both forms of the invention illustrated, the blades may be changed merely by flexing the plate 12 or 12' in a direction to spread the bent ends 16 or 16' of the plate outwardly. In the form shown in Fig. 9, such plate may be thus flexed by moving the elements 17 to the opposite side of the holder and pinching such elements toward each

other. When thus flexed, the plate 11 and its blade will easily snap out of the holder.

In Fig. 29, I have illustrated a further modification wherein the blade holder 61 is a permanent part of the blade 10, such holder being provided with pivot pins 59' at its ends and an adjacent pin 60' at one end thereof. Such holder pins correspond to those shown in Fig. 27. Thus it will be seen that, in accordance with the scope of the invention, the holder may be either a permanent or a removable part of the blade, it only being necessary that means be provided on the ends of the blade for pivotally mounting the same for stropping.

What I claim is:

1. A blade holder comprising a relatively thin flexible plate adapted to engage one side of a safety razor blade, means cooperating with the plate and adapted to engage the opposite side of the blade to hold the blade clamped therebetween, and means at the ends of the holder for supporting the same for pivotal movement about the central longitudinal axis of the blade held therein, the plate with a blade held thereby being adapted to bodily flex to the shape of the razor clamping surface therefor.

2. A blade holder comprising two relatively thin flexible plates adapted to support a safety razor blade therebetween, and means cooperating with the plates for holding the same together with a blade clamped therebetween, the plates with a blade held therebetween being adapted to bodily flex to the shape of the razor clamping surfaces therefor.

3. A blade holder comprising two relatively thin flexible plates adapted to support a safety razor blade therebetween, and laterally extending means integral with one of the plates and adapted to engage the other plate for holding the plates together with a blade held therebetween, the plates with a blade held therebetween being adapted to bodily flex to the shape of the razor clamping surfaces therefor.

4. A blade holder comprising two relatively thin flexible plates adapted to support a safety razor blade therebetween, the plates being perforated and one plate having integral means about its perforation adapted to engage within a cooperating perforation in the other plate, and flexible means for securing the plates together with a blade clamped therebetween, the plates with a blade held therebetween being adapted to bodily flex to the shape of the razor clamping surfaces therefor.

5. A blade holder comprising two relatively thin flexible plates adapted to support a safety razor blade therebetween, means cooperating with the plates for holding the same together with a blade clamped therebetween, and means at the ends of one

of the plates for pivotally supporting the holder and a blade therein for stropping, the plates with a blade held therebetween being adapted to bodily flex to the shape of the razor clamping surfaces therefor.

6. A safety razor of the double-edge type comprising the combination of a head having a transversely curved blade supporting surface, a handle secured to the head, a flexible blade holder having means on the ends thereof for pivotally mounting the holder with a blade therein for stropping, a removable guard having a transversely curved blade engaging surface for cooperating with the curved surface of the head, and means providing a relative approaching movement between the guard and head for clamping the holder with its blade therein in shaving position between the curved surfaces of the guard and head, the flexible blade holder with a blade therein being adapted to flex to the shape of the said transversely curved blade supporting surfaces when the parts are clamped in the shaving position.

7. A safety razor of the double-edge type comprising the combination of a head having a blade supporting surface and guard teeth along opposite edges thereof, a handle secured to the head, a flexible blade holder having means on the ends thereof for pivotally mounting the holder with a blade therein for stropping, a removable guard cooperating with the head, certain of the adjacent surfaces of the head and guard being recessed to receive the blade holder, and means for drawing the guard toward the head in a manner to seat the holder in the recessed portion and to clamp the blade therein in shaving position between the adjacent surfaces of the head and guard with the cutting edges of the blade positioned along the said guard teeth, the flexible blade holder being adapted to flex to conform to the shape of the said head and guard recesses when the parts are clamped in the shaving position.

8. A safety razor of the double-edge type comprising the combination of a head having a blade supporting surface and guard teeth along opposite edges thereof, a handle secured to the head, a flexible blade holder having means on the ends thereof for pivotally mounting the holder with a blade therein for stropping, the said holder including two relatively thin plates adapted to support a blade therebetween, a removable guard cooperating with the head, the adjacent surfaces of the head and guard being recessed to receive the blade holder therein, and screw threaded means for drawing the guard toward the head in a manner to seat the holder in the said recesses and to clamp the blade therein in shaving position between the adjacent surfaces of the head and guard

with the cutting edges of the blade positioned along the said guard teeth, the flexible blade holder being adapted to flex to conform to the shape of the said head and guard recesses when the parts are clamped in the shaving position.

9. A safety razor of the double-edge type comprising the combination of a head having a blade supporting surface and guard teeth along opposite edges thereof, a handle rigidly secured to the head, a blade holder provided with a pivot pin on one end and pivot means on its other end including a pinion for pivotally mounting the holder with a blade therein for stropping, a removable guard, and means for drawing the guard toward the head for clamping the blade therein in shaving position between the adjacent surfaces of the head and guard with the cutting edges of the blade positioned along the said guard teeth, the said pinion being adapted to cooperate with stropping mechanism for automatically pivoting the blade into engagement with the strop during the stropping operation.

10. In combination, a safety razor of the double-edge type comprising a head having a blade supporting surface and guard means along opposite edges thereof, a handle secured to the head, a blade holder pivotally mounted on the head and adapted to have a bodily movement away from the head to a position for stropping a blade held therein, means for rigidly clamping the holder with its blade therein in shaving position in the razor with the cutting edges of the blade positioned along the said guard means, and a stropper having means for supporting the razor therein and for simultaneously stropping two edges of the blade while thus supported.

11. In combination, a safety razor of the double-edge type comprising a head having a blade supporting surface, a handle secured rigidly to the head, a blade holder pivotally mounted on the head and adapted to have a bodily movement away from the head to a position for stropping a blade held therein, a removable guard, certain of the adjacent surfaces of the head and guard being recessed to receive the blade holder, means for drawing the guard toward the head in a manner to seat the holder in the recessed position and to clamp the blade therein in shaving position between the adjacent surfaces of the head and guard, and a stropper having means for supporting the razor therein and for simultaneously stropping two edges of the blade while thus supported.

12. A safety razor blade holder in combination with a safety razor and a stropper, comprising means for rigidly supporting the holder and its blade in the razor in shaving position, means for pivotally supporting the holder and its blade in the

- stropper, and means including a long flexible strop cooperating with the stropper and holder for stropping the blade while thus pivotally supported, the razor and stropper being independent units.
13. A safety razor blade holder in combination with a safety razor and a stropper, comprising an inner guard and an outer guard and means providing a relative approaching movement of the guards to clamp the holder with its blade in shaving position therebetween in the razor, means for pivotally supporting the holder and its blade in the stropper, and means including a long flexible strop cooperating with the stropper and holder for stropping the blade while thus pivotally supported, the razor and stropper being independent units.
14. A safety razor blade holder in combination with a safety razor and a stropper, comprising an inner guard and an outer guard certain of the blade holder engaging surfaces of which are recessed to receive the holder, screw threaded means for drawing the outer guard toward the inner guard in a manner to seat the holder in the recessed portion and to clamp the blade therein in shaving position in the razor between the adjacent surfaces of the guards, means for pivotally supporting the holder and its blade in the stropper, and means including a long flexible strop cooperating with the stropper and holder for stropping the blade while thus pivotally supported, the razor and stropper being independent units.
15. A holder for a double-edged safety razor blade in combination with a razor therefor and a stropper, comprising means for mounting the holder and its blade in the razor in shaving position, means for supporting the holder and blade in the stropper for pivotal movement about the central longitudinal axis of the blade, and means in the stropper for stropping the blade while thus pivotally supported, the razor and stropper being independent units.
16. A holder for a double-edged safety razor blade in combination with a razor therefor and a stropper, comprising means for mounting the holder and its blade in the razor in shaving position, means for supporting the holder and blade in the stropper for pivotal movement about the central longitudinal axis of the blade, and means including a long flexible strop cooperating with the stropper and holder for stropping both edges of the blade and for oscillating the blade about its said central axis as the direction of movement of the strop reverses, the razor and stropper being independent units.
17. A holder for a double-edged safety razor blade in combination with a razor therefor and a stropper, comprising an inner guard and an outer guard certain of the blade holder engaging surfaces of which are recessed to receive the holder, means for drawing the outer guard toward the inner guard in a manner to seat the holder in the recessed portion and to clamp the blade therein in shaving position in the razor between the adjacent surfaces of the guards, means for supporting the holder and blade in the stropper for pivotal movement about the central longitudinal axis of the blade, and means including a long flexible strop cooperating with the stropper and holder for stropping the blade while thus pivotally supported, the razor and stropper being independent units.
18. A holder for a double-edged safety razor blade in combination with a razor therefor and a stropper, comprising an inner guard having a transversely curved blade supporting surface and guard teeth along opposite edges thereof, an outer removable guard cooperating therewith and means providing a relative approaching movement of the guards to clamp the holder with its blade in a transversely curved shaving position between such guards on the razor, the cutting edges of the blade being positioned along the said guard teeth, means for supporting the holder and blade in the stropper for pivotal movement about the central longitudinal axis of the blade, and means including a long flexible strop cooperating with the stropper and holder for stropping both edges of the blade and for oscillating the blade about its said central axis as the direction of movement of the strop reverses.
19. A holder for a double-edged safety razor blade in combination with a razor therefor and a stropper, comprising an inner guard and an outer guard having adjacent transversely curved blade engaging surfaces, a handle secured to the inner guard, screw threaded means in connection with the handle, providing a relative approaching movement of the guards to clamp the holder with its blade in a transversely curved shaving position between such guards on the razor, means for supporting the holder and blade in the stropper for pivotal movement about the central longitudinal axis of the blade, and means in the stropper for stropping the blade while thus pivotally supported.
20. A holder for a double-edged safety razor blade in combination with a razor therefor and a stropper, comprising means for mounting the holder and its blade in the razor in shaving position, the holder and its blade being bodily removable from the razor, means on the stropper for supporting the holder and blade therein for pivotal movement about the central longitudinal axis of the blade, and means in the stropper for stropping the blade while thus pivotally supported, the razor and stropper being independent units.

21. A holder for a double-edged safety razor blade in combination with a razor therefor and a stropper, comprising an inner guard and an outer guard certain of the 5 blade holder engaging surfaces of which are recessed to receive the holder, means providing a relative approaching movement of the guards to clamp the holder with its blade in shaving position between such guards on 10 the razor, the holder and its blade being bodily removable from the razor, means on the stropper for engaging the ends of the holder to support the holder and blade therein for pivotal movement about the central longitudinal axis of the blade, and means in the 15 stropper for stropping the blade while thus pivotally supported.

In testimony whereof, I hereto affix my signature.

LAWRIE L. WITTER.
